E. SCHNURRENBERGER.
PROCESS OF DEGUMMING SILK.
APPLICATION FILED NOV. 28, 1911.

1,026,000.

Patented May 14, 1912.

UNITED STATES PATENT OFFICE.

EMIL SCHNURRENBERGER, OF PATERSON, NEW JERSEY, ASSIGNOR TO WEIDMANN
SILK DYEING CO., OF PATERSON, NEW JERSEY, A CORPORATION OF NEW JERSEY.

PROCESS OF DEGUMMING SILK.

1,026,000.

Specification of Letters Patent.

Patented May 14, 1912.

Application filed November 29, 1911. Serial No. 663,053.

To all whom it may concern:

Be it known that I, EMIL SCHNURRENBERGER, a citizen of the United States, residing at Paterson, in the county of Passaic 5 and State of New Jersey, have invented certain new and useful Improvements in Processes of Degumming Silk, of which the following is a specification.

This invention consists in an improved 10 process of removing the gum which exists on silk in its natural state. According to this process, the silk, say in the form of skeins, is placed in a suitable vat or chest, being strung on and suspended from sticks 15 or rollers which may be turned so as to permit altering the relation of the silk thereto for a purpose to be indicated. This chest or vat is open at the top and has a cover which, by being hinged or removable, allows access 20 to the interior of the chest but which more or less closely seals the opening when in the closed position. Otherwise, except for a vent at the bottom of the chest or vat whose purpose will later appear, the chest may be 25 and preferably is both air and steam tight. Having suspended the skeins in the vessel, by suitable spraying means leading into the same preferably above the silk, soap solution is sprayed upon the silk, well soaking 30 the same. Then, by suitable means also entering the chest or vat, the silk is subjected to a steam bath, say by delivering steam in a free state into the vessel, so that the soaped silk is thoroughly acted upon by the steam 35 or vapor, the steaming operation being continued for a suitable length of time, varying from ten to twenty minutes, according to the nature of the silk. The conjoint effect of the soap solution and steam being the 40 active factor in the removal of the gum, it is advisable either to repeat the admission of the soap solution from time to time during each steaming operation or keep the solution constantly sprayed on the silk. 45 Moreover, since the efficiency and the expediting of the process will of course be materially enhanced the more effective the steam is in its action on the soaped silk, the performance of the process in a closed vessel 50 whose communication with the atmosphere is restricted, say at the vent, so that at the very outset even air is excluded, leaving only steam within the vessel, is highly advantageous. The vent allows the escape

of the drippings of the soap solution, which may thus be recovered and re-used.

During the treatment the sticks or rollers are turned from time to time, or in some other way the relation of the silk thereto altered, so that the part of the silk in contact with the sticks or rollers at one stage in the process will be clear thereof at another stage and so more thoroughly receive the effects of the treatment. As the final step in the treatment the silk is washed by clean hot water, which is preferably sprayed onto the silk in any suitable way, say by the spraying means utilized in the spraying of the soap solution; when the released gum has been washed off in this manner, the silk may be removed from the chest or vat. In this treatment the action of the soap and steam is accomplished without those disadvantageous results, such as disturbance of the fibers of the silk and the snarling or disarranging of the strands thereof, which accompany the usual treatment consisting in soaking the silk in a hot soap solution. It is moreover found that the treatment is more thorough and expeditious than that commonly practised in that the steam and the soap solution are more effectively impregnative and otherwise influential on the gummed silk than any treatment involving immersing the silk in a liquid bath.

An apparatus suitable for the carrying out of the improved process is shown in the accompanying drawing wherein the single figure shows the apparatus in section.

a is a chest or vat having a hinged cover *b* which closely fits the open top of said chest or vat. Along one side thereof are arranged a series of sockets *c* for the ends of the rollers *d* which are journaled in said sockets and at their opposite ends are received by the rotary sockets *e* suitably fitted thereto so that the rollers will turn on turning said sockets *e*. Sockets *e* carry bevel pinions *f* meshing with bevel pinions *g* on a shaft *h* suitably journaled on the outside of the vat or chest and having a crank *i* whereby to turn it. Above the skeins *A*, which are strung on and hang suspended from the rollers, is a perforated spraying coil *j*. Below the skeins, at the bottom of the vat, is a coil *k*, also perforated. Above the coil *k* is preferably a perforated diaphragm *l*, serving to prevent the steam issuing from the coil from spouting

against the skeins and acting to disseminate the escaping steam.

m is a tank for the soap solution; *n* a tank for hot washing water. From these tanks 5 lead the pipes *o* and *p*, having valves *o'* and *p'* and merging into a pipe *q* which communicates with the coil *j*.

r is a reservoir into which the drippings of soap solution drain from the vat or chest 10 by way of the vent *s* which may have two outlets *s'* and *s''* controlled by two cocks *t'* and *t''* so that either the soap solution may be discharged into the reservoir (by outlet *s'*) or the washing water conducted away 15 outside of said reservoir. *u* is a pipe, provided with a pump *v*, for returning the contents of the reservoir to the tank *m*. The washing step is preferably, though not necessarily, performed while the silk is still 20 within the vessel after the treatment with steam and soap solution.

Having thus fully described my invention, what I claim as new and desire to secure by Letters Patent is:—

25 1. The herein-described process of separating the gum from silk which consists in placing the silk in a suitable receptacle, wetting the silk while in said receptacle with soap in solution, treating the silk with a 30 steam bath while still in said receptacle and while wet with the soap solution, and finally washing the silk, substantially as described.

2. The herein-described process of separating the gum from silk which consists in

placing the silk in a suitable receptacle, 35 wetting the silk while in said receptacle with soap in solution, filling the receptacle with free steam while the silk is still in said receptacle and still wet with the soap solution, and finally washing the silk, substantially as described.

3. The herein described process of separating the gum from silk which consists in placing the silk in a suitable vessel and, while in said vessel, spraying the silk with 45 soap solution and treating the silk with a steam bath, and finally washing the silk, substantially as described.

4. The herein described process of separating the gum from silk which consists in 50 placing the silk in a substantially closed vessel, then, while in said vessel, spraying the silk with soap solution and filling the vessel with free steam, and finally washing the silk, substantially as described. 55

5. The herein described process of separating the gum from silk which consists in placing the silk in a substantially closed vessel, then, while in said vessel, spraying the silk with soap solution and simultaneously filling the vessel with free steam, substantially as described. 60

In testimony whereof I affix my signature in presence of two witnesses.

EMIL SCHNURRENBERGER.
